MAGNIFYING DEVICE

Filed June 26, 1929

UNITED STATES PATENT OFFICE

OTTO RENNICKE, OF NEW YORK, N. Y.

MAGNIFYING DEVICE

Application filed June 26, 1929. Serial No. 373,722.

This invention relates to magnifying devices and particularly to devices of this class wherein the lens or lens supporting member is capable of longitudinal and transverse adjustment to position the lens of said member in proper alignment over a workpiece or article arranged on the device; and the object of the invention is to provide a device of the class specified involving a base plate or frame with means at one side portion and upon the upper face thereof for supporting an article or workpiece thereon, and with means at the other side of the frame for adjustably mounting and guiding a lens supporting member with respect to the workpiece supported in said frame, said means comprising a plurality of transversely spaced bars forming guide channels or recesses in which the lens supporting member or a part thereof is frictionally and tensionally supported; a further object being to provide a lens supporting member comprising an L-shaped arm part with which the lens frame is pivotally supported whereby said frame and lens may be moved into different positions and adjusted to focus the lens with respect to the work; and with these and other objects in view, the invention consists in a device of the class described and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a plan view of a device made according to my invention and indicating the method of its use.

Fig. 2 is an end view of the device as seen in Fig. 1; and,

Fig. 3 is a section on the line 3—3 of Fig. 1. In practice, I provide a base plate or frame 5 which may be of any desired form and construction but which is preferably fashioned from sheet metal and is provided with depending peripheral flanges 6 to form a recess 7 in the bottom of the frame, the top plate

of the frame being pressed downwardly at one side thereof to form an oblong, elongated aperture 8, the contour of which is such as to receive a slide rule 9 of conventional size and form, it being understood at this time, however, that a tool or workpiece of any kind or class may be supported upon the frame and the frame fashioned to suit the particular workpiece. In connection with rulers, it will also be apparent that the frame may be fashioned to accommodate rulers of various dimensions, the ruler 9 in the construction shown having three scales 9a, 9b and 9c arranged longitudinally thereof, parts of the scales being shown in the accompanying drawing. It is in connection with these scales, that the lens of the device, later described, is adapted to cooperate. As in all slide rules, a slide rule bar 10 is employed.

At the other side of the frame 5 and extending longitudinally thereof are four bars 11, 12, 13 and 14, the ends of which are supported in keepers 15 riveted or otherwise secured to the upper face of the frame as seen at 16, note Fig. 3. Pivoted to the upper ends of the keepers 15, as seen at 17, are handle members 18 which may be extended into the position shown in full lines in Figs. 1, 2 and 3 and moved into the position indicated in dot and dash lines in Fig. 1.

The bars 11 to 14 inclusive are spaced apart within the keepers 15 by washers or other spacing members 19, note Figs. 2 and 3 and are held in position by pins or rivets 20 which pass through the ends of said bars and said washers, thus forming between the keepers 15, three longitudinal channels or passages 21, 22 and 23 into which the lower end portion of the L-shaped or angular part 24 of the lens supporting member 25 is adapted to be placed. The member 25 includes a lens frame 26 pivoted to the angular portion of the part 25 as seen at 27 and in which the magnifying lens 28 is supported as clearly seen in Fig. 3 of the drawing.

It will be seen upon a consideration of the drawing that the part 24 of the member 25 may be placed in either one of the three channels, 21, 22 and 23 and may be moved longitudinally of the channels to arrange the lens

at any desired point longitudinally of the ruler 9. When said member is in the channel 21, the lens will be in position to read the characters in the scale line 9a; and when in 5 the channel 22 the scale line 9b; and when in the channel 23, the scale line 9c.

The usual pointer or marker frame 10a is arranged to slidably engage the ruler proper and includes a glass panel 10b upon which 10 is arranged the transverse line 10c, note Fig. 1, this construction being common in slide rulers of conventional form.

It will be understood that by virtue of the pivotal or hinge mounting of the part 26 15 in connection with the part 24, the same may be moved into the position indicated in dotted lines in Fig. 2 of the drawing or may be slightly adjusted with respect to the full line position, principally for the purpose of 20 focusing the lines with respect to the ruler or other workpiece.

It will also be understood that my invention is not necessarily limited to the use of the device in connection with rulers of the 25 class under consideration as workpieces of any kind or class may be arranged upon the frame and the member 25 adjustable with respect thereto to more clearly examine any part or section of the workpiece disposed 20 within the path of adjustable movement of the lens supporting member. In the construction shown, it will be understood that the part 24 of said member is frictionally and tensionally supported in the recesses or channels formed between the separate bars employed, and various other changes in and modifications of the construction herein shown and described may be made within the scope of the appended claims without 60 departing from the spirit of my invention or sacrificing its advantages.

Having fully described my invention, what I claim as new and desire to secure by Letters Patent, is:

1. A device for magnifying portions of a slide ruler or the like, comprising an elongated plate, the upper surface of said plate having an elongated recess in which the ruler is adapted to be placed to expose one surface 5 thereof, a plurality of guideways on the upper surface of said plate and in parallel relation with reference to said recess and spaced transversely with respect thereto, a lens supporting frame detachably supported in connection with said guideways and movable longitudinally with respect thereto; and said frame having a lens supporting part arranged over and movable transversely and longitudinally of said recess.

2. A device for magnifying portions of a slide ruler or the like, comprising an elongated plate, the upper surface of said plate having an elongated recess in which the ruler is adapted to be placed to expose one surface 65 thereof, a plurality of guideways on the up-

per surface of said plate and in parallel relation with reference to said recess and spaced transversely with respect thereto, a lens supporting frame detachably supported in connection with said guideways and movable longitudinally with respect thereto, and said 70 frame having a lens supporting part arranged over and movable transversely and longitudinally of said recess, the lens supporting part of said frame having a pivotal support to permit its movement into different angular positions.

3. A device for magnifying portions of a slide ruler or the like, comprising an elongated plate, the upper surface of said plate having an elongated recess in which the ruler is adapted to be placed to expose one surface 80 thereof, a plurality of guideways on the upper surface of said plate and in parallel relation with reference to said recess and spaced transversely with respect thereto, a lens supporting frame detachably supported in connection with said guideways and movable longitudinally with respect thereto, and said frame having a lens supporting part arranged over and movable transversely and longitudinally of said recess, the lens supporting part of said frame having a pivotal support to permit its movement into different angular positions, and the other part of said 85 frame being L-shaped in form.

4. A device for magnifying portions of a slide ruler or the like, comprising an elongated plate, the upper surface of said plate having an elongated recess in which the ruler is adapted to be placed to expose one surface 90 thereof, a plurality of guideways on the upper surface of said plate and in parallel relation with reference to said recess and spaced transversely with respect thereto, a lens supporting frame detachably supported in connection with said guideways and movable longitudinally with respect thereto, and said frame having a lens supporting part arranged over and movable transversely and longitudinally of said recess, the lens supporting part of said frame having a pivotal support to permit its movement into different angular positions, and the other part of said 95 frame being L-shaped in form, and said 100 guideways being formed of a plurality of bars arranged in parallel and spaced relation with reference to each other; and means at the ends of said bars for securing the same to said plate and for spacing the same one from the 105 other.

5. A device for magnifying portions of a slide ruler or the like, comprising an elongated plate, the upper surface of said plate having an elongated recess in which the ruler is adapted to be placed to expose one surface 110 thereof, a plurality of guideways on the upper surface of said plate and in parallel relation with reference to said recess and spaced transversely with respect thereto, a lens sup- 115 120 125 130

- porting frame detachably supported in connection with said guideways and movable longitudinally with respect thereto, and said frame having a lens supporting part arranged over and movable transversely and longitudinally of said recess, the lens supporting part of said frame having a pivotal support to permit its movement into different angular positions, the other part of said frame being L-shaped in form, said guideways being formed of a plurality of bars arranged in parallel and spaced relation with reference to each other and means at the ends of said bars for securing the same to said plate and for spacing the same one from the other, and handle members pivotally supported in connection with the ends of said plate.
6. A device of the class described comprising an elongated plate, means for supporting an elongated article against shifting movement upon the upper face of said plate, a plurality of bars mounted on the upper face of said plate in parallel relation to said means and to each other, said bars being spaced apart to form guide channels, a lens supporting frame, one end of which is adapted to be frictionally passed into said channels and movable longitudinally thereof, and the other end of said frame having a lens supporting part arranged over said first named means and movable with respect thereto in the adjustable movement of said frame in said channels.
7. A device of the class described comprising an elongated plate, means for supporting an elongated article against shifting movement upon the upper face of said plate, a plurality of bars mounted on the upper face of said plate in parallel relation to said means and to each other, said bars being spaced apart to form guide channels, a lens supporting frame, one end of which is adapted to be frictionally passed into said channels and movable longitudinally thereof, the other end of said frame having a lens supporting part arranged over said first named means and movable with respect thereto in the adjustable movement of said frame in said channels, and said lens supporting part being pivoted to permit movement of said part into different angular positions with respect to the first named means.
8. A device of the class described comprising an elongated plate, means for supporting an elongated article against shifting movement upon the upper face of said plate, a plurality of bars mounted on the upper face of said plate in parallel relation to said means and to each other, said bars being spaced apart to form guide channels, a lens supporting frame, one end of which is adapted to be frictionally passed into said channels and movable longitudinally thereof, the other end of said frame having a lens supporting part arranged over said first named means and movable with respect thereto in the adjustable movement of said frame in said channels, said lens supporting part being pivoted to permit movement of said part into different angular positions with respect to the first named means.
9. The combination with a slide ruler of a magnifying device comprising an elongated plate, the upper surface of which is provided with a recess in which the ruler is placed to prevent movement of the ruler with respect thereto, a plurality of guideways arranged on the upper face of said plate at one side of said recess and in spaced, parallel relation with respect thereto, and a lens supporting frame, detachably and adjustably supported in connection with said guideways to arrange the lens thereof in different positions transversely with respect to the ruler supported in said recess as well as longitudinally thereof.
10. The combination with a slide ruler of a magnifying device comprising an elongated plate, the upper surface of which is provided with a recess in which the ruler is placed to prevent movement of the ruler with respect thereto, a plurality of guideways arranged on the upper face of said plate at one side of said recess and in spaced, parallel relation with respect thereto, and a lens supporting frame, detachably and adjustably supported in connection with said guideways to arrange the lens thereof in different positions transversely with respect to the ruler supported in said recess as well as longitudinally thereof, said frame including a pivotally mounted lens supporting part.
11. The combination with a slide ruler of a magnifying device comprising an elongated plate, the upper surface of which is provided with a recess in which the ruler is placed to prevent movement of the ruler with respect thereto, a plurality of guideways arranged on the upper face of said plate at one side of said recess and in spaced, parallel relation with respect thereto, a lens supporting frame, detachably and adjustably supported in connection with said guideways to arrange the lens thereof in different positions transversely with respect to the ruler supported in said recess as well as longitudinally thereof, said frame including a pivotally mounted lens supporting part, and said guideways being formed by a plurality of bars arranged in spaced parallel relation to each other, and means at the ends of said bars for coupling the same together and to said plate.
12. The combination with a slide ruler of a magnifying device comprising an elongated plate, the upper surface of which is provided

with a recess in which the ruler is placed to prevent movement of the ruler with respect thereto, a plurality of guideways arranged on the upper face of said plate at 5 one side of said recess and in spaced, parallel relation with respect thereto, a lens supporting frame, detachably and adjustably supported in connection with said guideways to arrange the lens thereof in different positions 10 transversely with respect to the ruler supported in said recess as well as longitudinally thereof, said frame including a pivotally mounted lens supporting part, said guideways being formed by a plurality of bars 15 arranged in spaced parallel relation to each other and means at the ends of said bars for coupling the same together and to said plate, and handle members pivotally supported in connection with said last named means. 20 In testimony that I claim the foregoing as my invention I have signed my name this 25th day of June, 1929.
